ABSTRACT

A gripper clamp is provided for facilitating the handling of screeds used in the rough levelling of concrete. The screeds are usually two by fours or two by sixes and are held by workmen at opposite ends. The handling of such screeds is simplified by the use of a gripping tool including a first handle having right angularly extending jaws to engage one side of the screed and a relatively movable handle pivotal relative to the first and having a jaw end engageable with the side of the screed engaged by the first-named jaws.

GRIPPER CLAMP FOR SCREEDS

This invention relates to an improvement in a gripper clamp for screeds and deals particularly with a tool useful in handling a screed used for the levelling of concrete and the like.

BACKGROUND OF THE INVENTION

There are various means for levelling concrete such as that used in floors of a building. In most such arrangements, spaced rails are provided, or a single rail is provided in spaced relation to the previously formed layer of concrete. The surface of the concrete is usually levelled to a generally acceptable level by means of a plank such as a two or four or two by six. Such a plank is usually difficult to handle and to use in levelling the surface of the floor. The present invention resides in the provision of the clamping device which may be used to hold the two by four or two by six plank used for levelling off the surface of the concrete, and which generally simplifies the operation of levelling the mass of concrete.

Concrete is usually laid between members designed to indicate a predetermined level. The general level is usually approximated by the use of a screed which is designed to remove the excess of concrete and to deposit such excess in the areas beneath the level of the screed. The screeds ordinarily used are planks of wood, commonly known as two by fours and two by sixes. Workers are provided at each end of such a plank, and the plank is usually reciprocated back and forth over the surface of the concrete so as to provide an approximate level. The surface may later be smoothed by suitable mechanism well known in the art.

One of the problems involved in the rough smoothing of the concrete lies in the difficulty in holding the two by four, or two by six, so that the excess cement will be removed, and the surface will be made at a certain level. The difficulty normally resides in the fact that it is difficult to hold a plank of this size in the hands for any great period of time while the surface of the concrete is being levelled. It is, therefore, a feature of the present invention to provide a gripping device for more comfortably handling screeds, and to accordingly speed up the process of finishing a concrete surface.

SUMMARY OF THE INVENTION

A feature of the present invention resides in the provision of a clamp including a pair of pivotally connected handles having generally right angularly extending end portions thereon. These end portions are arranged so that a two by four or two by six may be engaged between the fixed jaws and the relatively movable jaw thereof. When the movable jaw is moved into an engagement with the member engaging the fixed jaws, the structure is such that the two by four or two by six may be readily moved back or forth, or moved in any desired direction, without the resulting strain on the fingers which is usually experienced in moving the plank across the surface to be smoothed. Furthermore, the clamp is such that the operator can hold the plank at a greater distance from his body than is possible with the usual screed, thereby providing a greater flexibility of operation.

A feature of the present invention resides in the provision of a clamp including a member designed to engage one side of the plank, and pivotally connected member designed to engage the other side thereof. By drawing the handle portions of the jaws together, the plank or screed is securely supported.

In the drawings forming a part of the specification:

FIG. 1 is a perspective view of the gripper clamp in readiness for operation.

FIG. 2 is a perspective view of the gripper clamp in engagement with the screed.

FIG. 3 is a side elevational view of the structure indicated in FIG. 2.

FIG. 4 is a bottom plan view of the end portion of the device, the position of the view being indicated by a line 4-4 of FIG. 3.

The device which is illustrated is extremely simple in its form. The device is preferably made of metal strips of generally rectangular section. The body portion of the device includes a pair of parallel sides 10 and 11 connected by a connecting loop 12. The ends of the arms 10 and 11 are twisted through an angle of 90° as indicated at 13 and 14, and the ends of the arms 10 and 11 terminate in generally coplanar arm portions 16 and 17.

In order to provide a clamping device, an arm 19 extends in generally parallel relation to the upper surfaces of the arms 10 and 11, and is right angularly twisted as indicated at 20 to extend between these arms 10 and 11. A pivot bolt 21 serves as a connection between the fixed arms 10 and 11 and the downwardly extending end 24 of the relatively movable arm 19. By pivoting the arm 19 toward the arms 10 and 11, a plank such as a two by four 22 may be engaged between the arm portions 16 and 17 and the downwardly projecting end 24 of the movable arm 19.

The metal strips such as strap iron, having wider sides and narrower edges, is arranged so that the wider a flat sides of the jaws 16 and 17 engage one side of the screed, while the narrower edge of the jaw 24 of the lever 19 engages the opposite side thereof.

The advantage of the present structure is believed obvious to one skilled in the art, but may not be obvious to those who are not skilled in the art. Concrete is usually laid roughly between a pair of parallel guides, and the concrete is usually levelled accordingly. While various devices have been used to level the concrete, in general, the level is usually determined by scraping off the excess concrete with the use of a plank or similar member which rests upon the rails or the like so as to provide the proper depth of the concrete. Planks such as two by fours or two by sixes are somewhat difficult to hold in the hand during such operations. However, clamps such as the disclosed in the present invention may be provided to greatly simplify the operation of levelling of the surface of concrete, and the levelling device is not of necessity held between the thumb and fingers, as is in the event of a levelling plank, but between the thumb and fingers in the manner usual in handling a pair of pliers or another tool of this type. Furthermore, the concrete levelling device is further enhanced by the fact that the levelling tool may be held from a position laterally of the concrete, rather than from either side of a body of concrete, as has been usual practice.

As will be noted in FIG. 4 of the drawings, the arm portions 16 and 17, while being described as generally coplanar are actually slightly angularly related. The outer edges of these arms are on a plane which is somewhat closer to the movable jaw 24 than inner edges thereof. This angularity between the jaws helps prevent slipping of the screed relative to the clamp when the screed is being moved in a lateral direction.

In accordance with the patent statutes, I have described the principals of operation and construction of my device, and while I have endeavored to set forth the best embodiment thereof, I desire to have it understood that changes may be made within the scope of the following claims without departing from the spirit of my invention.

I claim:

1. A gripper clamp for use in handling screeds and the like including:
  - a pair of levers formed of metal strips of generally rectangular cross section having parallel sides and parallel connecting edges,
  - a first of said levers including a pair of arms, the sides of which are generally parallel and the edges of which are substantially coplanar,
  - a loop connecting one end of said arms together, said arms being twisted at their other ends through an angle of substantially 90° so that the strip sides are generally coplanar,
  - arm portions extending at generally right angles to said other ends,

a second of said levers having handle portion of one end with its sides in substantially right angular relation to the sides of said first lever arms and having a handle portion at one end and,
 said second lever being twisted at substantially right angles to the sides of said handle portion of second lever,
 an end on said second lever forming a jaw bent at substantially ninety degrees from the sides of said handle portion of said second lever,
 said end of said second lever extending between the parallel 10

arms of said first lever and pivoted thereto.
 2. The structure of claim 1 and in which the sides of said arm portions of said first lever extending at substantially right angles to said other ends thereof are angularly related with the outer edges thereof on a plane slightly farther from said jaw than the inner opposed edges thereof.

3. The structure of claim 1 and in which one of the edges of said second lever provides a gripping edge of said jaw.
